UNITED STATES PATENT OFFICE.

MILLER REESE HUTCHISON, OF WEST ORANGE, NEW JERSEY, ASSIGNOR TO MILLER REESE HUTCHISON, INC., A CORPORATION OF NEW JERSEY.

LOCK-CABINET FOR PHONOGRAPH-RECORDS.

1,351,333.

Specification of Letters Patent. Patented Aug. 31, 1920.

Application filed June 3, 1919. Serial No. 301,520.

To all whom it may concern:

Be it known that I, MILLER REESE HUTCHISON, a citizen of the United States, and resident of West Orange, in the county of Essex 5 and State of New Jersey, have invented certain new and useful Improvements in Lock-Cabinets for Phonograph-Records, of which the following is a specification.

This invention relates to filing fixtures or 10 furniture, and with regard to its more specific features, to filing cabinets for phonograph records.

One of the objects of the invention is to provide a device of the above type, of compact and relatively simple construction, 15 which shall be substantially proof against incorrect replacement of articles removed therefrom.

Another object is to provide a fixture of 20 the character referred to, which shall effectively bring about the result of maintaining the articles when not in use, in their proper place at all times.

Other objects will be in part obvious and 25 in part pointed out hereinafter.

The invention accordingly consists in the features of construction, combinations of elements and arrangement of parts which will be exemplified in the construction hereinafter described, and the scope of the application of which will be pointed out in the following claims.

Referring now to the accompanying drawings wherein is shown one of various possible embodiments of the several features of the invention,

Figure 1 is a view in longitudinal section taken along the line 1—1 of Fig. 3 and showing a carriage frame and its associated record locked in place.

Fig. 2 is a view similar to Fig. 1, showing the position of the parts when the record is free to be removed, and showing superposed cabinet sections.

Fig. 3 is a front view of Fig. 2 partly in section.

Fig. 4 is a fragmentary view on an enlarged scale, showing the key controlled elements and associated parts.

Fig. 5 is a fragmentary view on an enlarged scale of the outer keyhole plate and the associated locking plate.

Fig. 6 is a sectional view taken along the line 6—6 of Fig. 4, and

Fig. 7 is a perspective view of the key. 55

Similar reference characters refer to similar parts throughout the several views of the drawings.

Referring now to Figs. 1, 2 and 3 of the drawings, I have shown a filing cabinet having lateral walls 1; a base 2, a top 3 and a rear wall 4. Parallel to the base spaced therefrom, and extending substantially the length and width thereof, I provide a base plate 5, preferably resting on and secured 60 to a filler block 6, extending the length of the casing, the filler block in turn being secured to the base by any desired means, not shown. A vertical wall or plate 7 connects said base and said base plate at the front 70 thereof, the base plate and the wall being preferably formed of a single sheet metal stamping.

A plurality of vertical dividing partitions 8, 8A, 8B, etc., extend parallel to the lateral members 1, and are preferably equally spaced by means of spacing blocks 9, 10, to form a plurality of compartments C, each for housing a disk record, each said compartment being determined by two adjoining 75 dividing partitions, the rear wall 4 of the cabinet, the base plate 5 and the top 3 thereof.

Each compartment C is provided with a carriage frame 11, all said frames being 80 identical, so that the description of one will apply to all.

Referring now to Figs. 1 and 2, the carriage frame is preferably formed of a single piece of a thickness slightly less than the width of compartment C and preferably includes a base portion 12, resting on the base plate 5, a vertical portion 13 adapted to come into proximity to the rear cabinet wall 4 when the record is locked in place, and an 90 arcuate seat 14 for the disk record 15 to be filed therein.

A plurality of locking devices are provided, one for each compartment. As these locking devices are all identical in the embodiment shown, the detailed description thereof which follows, is understood to apply to each of the compartments. Referring now to Fig. 1 of the drawings, I have shown disposed between the base 2 and the base 100 plate 5, a locking latch 16, having a dog 17 urged by a spring 18 into cooperation with a notch 19 in the lowermost edge of the car-

riage frame 11. The spring 18 may be of any appropriate type but preferably has one end 20 secured to the latch and the other end 21 abutting the base member 2. A rod 35 extends transversely of the cabinet, and preferably constitutes the pivot for the locking latch 16 of each of the compartments, as best shown in Fig. 4, washers 36 being interposed between consecutive locking latches. 10 The vertical wall or plate 7 is provided with key holes 37, one aligned with each of the latches 16, to permit release of any frame by inserting and operating an appropriate key 38 in the corresponding keyhole, to retract 15 the corresponding latch.

To lock the record 15 into the carriage frame, I provide a curved locking arm 22, pivoted about a rod 23, extending transversely of the cabinet and secured to side walls 1. The locking arm has preferably an arcuate edge 24 substantially in contact with a portion of the periphery of the record 15, said arm being formed substantially of the same thickness of material as the carriage frame. The rod 23 serves as a pivot for the locking arm in each of the compartments C. 20 25

Rigid with locking arm 22 and accordingly also pivoted about rod 23, forming a bell-crank in combination therewith, I provide a shifting arm 25, the lower end of which is preferably slotted as at 26 to straddle a pin 27 on the carriage frame 11. The shifting arm extends to one side of the record 15, and is preferably formed of sheet metal. 30 35

To the rear of the carriage 11, I preferably secure as at 28, one end of a leaf spring 29, said spring being under compression when the frame 11 is in place as in Fig. 1, the free end of said spring abutting the rear wall 4, whereby the carriage frame 10 will be partially ejected by said spring, when the locking latch 16 is retracted. 40

Near the uppermost portion of the carriage frame, I provide a stop locking bar 30 pivoted intermediate its ends as at 31. The upper end of said bar is preferably weighted as at 32, the carriage frame being preferably of reduced thickness as at 34, so that the bar 30 can readily be accommodated within the compartment C. 45 50

Mechanism is provided, now to be described, which will prevent removal of any record until all of the other records are in place within the cabinet. 55

For this purpose I provide an angle plate 39 to the rear of the keyhole plate 7, said plate having a horizontal portion 40 resting on and secured to a plate support 41, which support in turn rests on the base 2 and is secured thereto by any desired means. The vertical portion 42 of the angle plate 39 constitutes an inside keyhole plate, having key- 60 65

holes 43 therein, one corresponding to each compartment C. The key holes 37 and 43 preferably extend at right angles to each other as indicated in Figs. 4 and 6. 65

Interposed between the keyhole wall 7 and the plate support 41, I provide a slide- 70 able keyhole plate 44, preferably extending the width of the cabinet. This keyhole plate has a plurality of preferably T-shaped perforations 45, providing stops 46, one said perforation corresponding to each keyhole 75 37. Said keyhole plate normally allows free entry therethrough of a key inserted into any of the keyholes 37. 80

The key employed for my cabinet is shown in detail in Fig. 7. This key comprises a handle portion 47 and a shank 46 having a bit 48 near the free end thereof and a similar bit 49 at an intermediate portion thereof, the two bits extending at right angles to each other. Between the handle and shank my key is provided with a flange 50, having a radial groove 51 at the uppermost part of the key when bit 48 points downwardly and of a width sufficient to lodge therein the thickness of the carriage frame 11. 85 90 95

In use, the custodian or operator inserts bit 48 of the key into the opening 37 corresponding to the record he wishes to play. The bit will readily pass through the corresponding opening 45 of the keyhole closing plate until it is arrested at the inside keyhole plate 42. The keyhole 43 in said latter element being at right angles to the bit 48, the key is turned through a corresponding angle, thereby allowing the said bit to register with said keyhole at the same time placing the second bit 49 into proper registry with keyhole 37 to permit the key to be inserted all the way. Thereupon the key is turned back through a right angle, whereby 100 both bits become operative at substantially the same time, bit 48 depressing the end of the locking lever 16 to remove the dog 17 from the slot 19, and bit 49 laterally displacing keyhole plate 44, thereby moving stops 110 46 to partially close or block each of the keyholes 37 other than the one through which the key is inserted, all as clearly shown in Figs. 4 and 5. The carriage frame 11 being now released, spring 29 expands to partially 115 eject said frame, the lower edge of which becomes lodged within slot 51 in the key flange 50. The pin 27 moves forwardly with the frame, thereby pivoting shifting arm 25 in a counterclockwise direction about rod 23 120 and correspondingly shifting locking arm 22 to release record 15 so that it may be removed, as shown in Fig. 2. 125

The carriage frame 11 cannot be pulled out beyond the position shown in Fig. 2, 125 when the locking arm 22 touches the top of the casing. When the record is removed, the weighted end 32 causes the locking lever 30

to swing in a clockwise direction to the position shown in Fig. 2, for a purpose appearing below.

In view of the fact that the key flange slot 51 embraces the lower edge of the carriage frame when the same is slid out, the key cannot be rotated to bring the bit 48 into registry with slot 43 so that the key cannot be withdrawn from the slot until the carriage frame is pushed to home position.

The position of the stop locking bar 30 in Fig. 2, however, prevents the carriage frame from being pushed home unless the removed record 15 or a similarly shaped article be inserted in the carriage frame to trip stop locking bar 30. Thus the key cannot be withdrawn until the carriage frame is pushed home, and the latter can be accomplished conveniently only after the record is reinserted.

Even if a duplicate of the key 38 be available, it cannot be used to gain access to any record other than the one removed, as stops 46 of the keyhole closing plate 44 prevent insertion of this key into any of the other keyholes.

The carriage frame 11 being now out of contact with the key flange as shown in Fig. 1, the key may readily be rotated back through a right angle to effect its removal, thereby allowing latch 16 to be snapped by its spring 18 into coöperation with notch 19 in the frame. In the process of turning the key, as is apparent, the bit 49 will shift the keyhole closing plate 44 to inoperative position where stops 46 no longer block the keyholes. The key may now again be used to release any of the records.

It is thus seen that by my invention only one record can be removed at a time, removal of such record both preventing the withdrawal of the key from the keyhole and blocking the remaining keyholes against insertion of a duplicate key. It is thus seen, that only a person having an appropriate key can remove a record from the cabinet, and even such person is compelled to replace the removed record and lock it in place before he can gain access to another. My invention thus at small effort on the part of the custodian or operator, effectively prevents confusion of the records, and minimizes the likelihood of breakage or scoring.

Although I prefer to employ the specific construction of locking means shown and described, including both a keyhole closing plate and a key locking means, it is to be understood that a construction omitting either of said elements and including the other, comes within the scope of my invention.

Although my invention has especial utility and its preferred application when applied to cabinets for disk phonograph

records, it is understood that it may be applied to numerous other purposes. In general, it achieves beneficial results where it is desirable to compel replacement of an article or apparatus to proper position in a fixture, before another article or apparatus can be removed therefrom.

Where a considerable number of phonograph records or the like, are to be filed, and it is desirable to save floor space, I may form my cabinet in sections providing an alinement plate 52 preferably somewhat less in width and length than the width and length of the casing on top of each section, and a correspondingly shaped cavity 53 in the bottom thereof. By this means, a plurality of cabinet sections may readily be superposed in proper alinement, each section having its cavity 53 filled by alinement plate 52 of the section below it.

It will thus be seen that there is herein described apparatus in which the several features of this invention are embodied, and which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent is:

1. In a cabinet for phonograph records, in combination, a plurality of compartments, each having a slidable carriage frame therein, each said frame being adapted to support a record, means responsive to the movement of any said frame to permit release of the corresponding record, and means to prevent release of any other record while said record is released.

2. In a filing cabinet for phonograph records, in combination, a plurality of compartments, each having a record locked therein and each having a corresponding keyhole, a single key to fit said keyholes for releasing any selected record, and means preventing the use of said key while a record is released.

3. In a cabinet for phonograph records, in combination, a plurality of compartments, each having a carriage frame locked therein, each said frame being adapted to seat a record, a single key for releasing any said frame, and means preventing use of said key while a frame is released.

4. In a cabinet for phonograph records, in

combination, a plurality of compartments, each having a slidable carriage frame locked therein, each said frame having means for locking a record with respect thereto, a key for releasing any said frame and the corresponding record, and means locking said key against withdrawal from the corresponding keyhole while said frame is released.

5. In a cabinet for phonograph records, 10 in combination, a plurality of compartments, each having a carriage frame therein for a record, a plurality of latches, one for locking each said frame into its compartment, a key for retracting any said latch to release the corresponding frame, and means locking said key against removal while said frame is released.

6. In a cabinet for phonograph records, 20 in combination, a plurality of compartments, each having a slidable carriage frame therein for a record, a plurality of spring-pressed latches, one for locking each said frame into its compartment, a key for retracting any said latch to release the corresponding frame, and means locking said key against removal when said frame is slid from home position.

7. In a cabinet for phonograph records, 30 in combination, a plurality of compartments, each having a carriage frame therein, a plurality of locking members, one associated with each frame for locking a record to a frame, a plurality of latches, one for locking each frame into its compartment, a single key for releasing any of said latches to permit removal of the corresponding record, and means to prevent use of said key for releasing any other latch while a record is removed.

40 8. In a cabinet for phonograph records, in combination, a plurality of compartments, each having a carriage frame therein, record locking means extending into the path of the records, a plurality of latches, 45 one for locking each said frame into the cabinet, means for retracting any one said latch, and means responsive to displacement of the corresponding frame, to release the corresponding record-locking means.

50 9. In a cabinet for phonograph records, in combination, a plurality of compartments, each having a carriage frame therein, locking means for locking a plurality of records one to each frame, a plurality of latches, one for locking each said frame into the cabinet, a single key for retracting any one said latch, and means to prevent use of said key until said record is again locked in place.

60 10. In a cabinet for phonograph records, 100 in combination, a plurality of compartments, each having a slidable carriage frame therein, a plurality of locking latches one for each frame, a key for releasing any said latch, and means interlocking said key with

said frame when slid outwardly to prevent removal of said key from its corresponding keyhole.

11. In a cabinet for phonograph records, 70 in combination, a plurality of compartments, each having a slidable carriage frame therein, a plurality of pivoted latches, one for locking each frame into said cabinet, a key for releasing any said latch, said key having a transverse flange, with a notch 75 interted by a frame when slid outwardly.

12. In a cabinet for phonograph records, 80 in combination, a plurality of compartments, each having a slidable carriage frame therein, a plurality of latches, one for locking each frame into said cabinet, a plurality of key holes, one corresponding to each said latch, a key having a bit adapted to be inserted into any said hole, said bit being adapted when said key is turned, to retract 85 said latch, and a flange on said key having a notch alined with the released frame to lodge the latter when slid outwardly.

13. In a cabinet for phonograph records, 90 in combination, a plurality of compartments, each having a carriage frame therein, locking means for locking a plurality of records one to each frame, a plurality of latches, one for locking each said frame into the cabinet, a key for retracting any one 95 said latch, and a connection between each frame and the corresponding record locking means for releasing the latter when the former is slid outwardly, and means to prevent use of said key until said record is again 100 locked in place.

14. In a phonograph record filing cabinet, in combination, a plurality of slidable carriage frames therein urged outwardly, each adapted to support a record, a locking latch 105 for each said frame, a key adapted to release any said latch, said key having a notch therein alined with and adapted to embrace the bottom of a released frame.

15. In a filing cabinet, in combination, a 110 plurality of compartments, each adapted to have an article locked therein, a key-hole associated with each compartment, a key adapted to be inserted into any said key-hole to unlock the corresponding article, and 115 means responsive to said manipulation of said key to prevent insertion of a key into any of a plurality of the remaining key-holes.

16. In a phonograph record filing cabinet, 120 in combination, a plurality of compartments, locking means for each compartment adapted to secure a record therein, a key-hole associated with each compartment, a key adapted to be inserted into any said key-hole 125 to unlock the corresponding record, and means responsive to said manipulation of said key to block the remaining key-holes.

17. In a phonograph record filing cabinet, 130 in combination, a plurality of compartments,

locking means for each compartment adapted to secure a record therein, a key-hole associated with each compartment, a key adapted to be inserted into any said key-hole 5 to unlock the corresponding record, and a key-hole closing plate to block the remaining key-holes responsive to the manipulation of said key.

18. In a phonograph record filing cabinet, 10 in combination, a plurality of compartments, locking means for each compartment adapted to secure a record therein, a key-hole associated with each compartment, a key adapted to be inserted into any said key-hole 15 to unlock the corresponding record, a key-hole closing plate normally in inobtrusive position, said key having a bit adapted during said unlocking movement to shift said plate to block the remaining key-holes.

19. In a phonograph record filing cabinet, 20 in combination a base, a base plate spaced therefrom, a wall connecting the front of said plate to said base, a plurality of compartments, locking means one associated 25 with each compartment to secure a record therein, a plurality of key-holes in said wall, one associated with each compartment to permit insertion of a key into any said hole to release the corresponding record, and a 30 key-hole closing plate in back of said wall and adapted to be shifted by said key during its releasing movement to block the remaining key-holes.

20. In a filing cabinet, in combination, a 35 plurality of compartments, a plurality of carriage frames, one in each compartment, a plurality of locking latches, one for each frame, a plurality of key-holes in said cabinet, one in alinement with each latch, and a 40 key-hole closing plate back of said key-holes, and normally inobtrusive, whereby a key with two bits may be inserted in any key-hole, and manipulated to permit one bit to release the corresponding latch, and simultaneously therewith to permit the other to shift said closing bar, to block the remaining key-holes.

21. In a filing cabinet, in combination, a base, a base plate spaced therefrom, a wall 50 connecting the front of said base plate and said base, a plurality of carriage frames over said base plate, a plurality of latches between said base and said base plate, one corresponding to each frame, and fitting in a 55 notch therein, a set of key-holes in said wall, one alined with each latch, an inner plate parallel to said wall and having key-holes at an angle to said first set, a key-hole closing plate in back of said wall, and a key having 60 two bits at an angle to each other, whereby upon insertion of said key in any of said key-holes, one bit will retract the latch to release the corresponding carriage frame, while the second shifts said closing plate, to 65 block the key-holes for the other latches.

22. In combination, in a filing cabinet, a plurality of locking members, each for locking an article into the cabinet, a key for releasing any said article, and means rendered operative by said releasing action to prevent 70 the withdrawal of said key from the corresponding keyhole, and to prevent use of a duplicate key for unlocking any other of the articles.

23. In combination, in a filing cabinet, a 75 plurality of locking members each for locking an article into the cabinet, a set of key-holes, one associated with each article, a key for releasing any said article, means rendered operative following said releasing action to prevent withdrawal of said key, and a 80 key-hole closing plate actuated by said key to block the remaining key-holes.

24. In a cabinet for phonograph records, in combination, a plurality of carriage 85 frames therein, each adapted to support a record, a plurality of locking elements, one for locking each said frame into said cabinet, a set of key-holes, one associated with each frame, a key for unlocking any said 90 element, means interlocking said frame and said key, while the corresponding record is removed to prevent withdrawal of said key, and a key-hole closing plate controlled by said key when in the latter position to 95 block the remaining key-holes against use of a duplicate key.

25. In a cabinet for phonograph records, in combination, a plurality of carriage 100 frames therein, each adapted to support a record, a plurality of latches, one for locking each said frame into said cabinet, a set of key-holes, one associated with each latch, a key for retracting any said latch to permit displacement of the corresponding frame, said key having a notch to prevent withdrawal thereof, by lodging said displaced frame therein, and means rendered operative by said retracting movement of said key, to 105 block the remaining key-holes.

26. In a cabinet for phonograph records, in combination, a plurality of carriage frames therein, a plurality of latches, one for locking each said frame into said cabinet, a set of key-holes, one associated with each latch, a key for retracting any said 110 latch to permit displacement of the corresponding frame, said key having a notch to prevent withdrawal thereof, by lodging said displaced frame therein, a plurality of locking arms, one associated with each frame and operative to lock a record therein, and means connecting each arm to its frame, to release the record when the frame is displaced.

27. In a filing cabinet, in combination, a 115 plurality of compartments, a plurality of slideable carriage frames, one in each compartment, each for lodging an article, a plurality of locking arms, one for locking each article to its frame, means connecting each 120

125 article to its frame, means connecting each 130

arm to its frame to permit release of the record when the frame is slid outwardly, a plurality of locking latches, one for locking each frame into the cabinet, a plurality of key-holes in the cabinet, one aligned with each latch, a key adapted to be inserted into any said key-hole to retract the corresponding latch, said key having a notch aligned with the associated frame, whereby when the released frame is slid outwardly, said key will be locked against withdrawal, and a key-hole closing plate back of said key-holes, rendered operative by said retracting movement of said key to block the remaining key-holes.

28. In a filing cabinet, in combination, a base, a base plate parallel thereto and spaced therefrom, a plurality of latches between said base and said base plate and having a common pivot rod, an outer key-hole plate connecting said base to said base plate, and having a key-hole aligned with each latch, an inner key-hole plate parallel to said outer plate, and having its key-holes at an angle to those of said outer plate, and a key-hole closing plate, between said key-hole plates.

29. In a phonograph record filing cabinet, in combination, a set of compartments, a set of slidable carriage frames, one locked in each compartment, each adapted to have a record locked therein, means to unlock any said frame, means responsive to displacement thereof, to unlock the corresponding record, and means to prevent the unlocking of any other frame until said record is reinserted and locked in place.

30. In a phonograph record filing cabinet, in combination, a set of compartments, a set of slidable carriage frames, one locked in each compartment, each adapted to have a record locked therein, a key to unlock any said frame, means responsive to displacement thereof, to unlock said record, and to prevent withdrawal of said key, and a stop locking bar to prevent reinsertion of said frame until after said record is reinserted therein.

31. In apparatus of the character described, in combination, a filing cabinet, a plurality of retainers therein, each for retaining an article, each said retainer exposing the corresponding article at the delivery side of the cabinet, and means in the path of each article to prevent removal thereof from its retainer, and means to lock each retainer into the cabinet.

32. In apparatus of the character described, in combination, a phonograph record cabinet, a plurality of dividing partitions therein forming compartments, a plurality of slidable carriage frames, one in each compartment, each exposing the corresponding record at the delivery side of the cabinet, a set of latches, one for locking each frame into the cabinet, a set of locking arms,

one for locking each record into its frame, each locking arm extending into the path for removal of the corresponding record, and means permitting release of a locking arm after the corresponding latch is withdrawn.

33. In apparatus of the character described, in combination, a compartment, a retaining member therein, adapted to hold an article, means preventing removal of said article when said retaining member is in home position, and a connection between said retaining member and said means for preventing operation of said means until said retaining member is displaced.

34. In apparatus of the character described, in combination, a phonograph record compartment accessible through one side, a movable carriage frame therein adapted to support a record and to expose the latter at the said accessible side of the compartment, a member interposed in the path of said record when said carriage is in home position, and means to render said member inobtrusive responsive to movement of said carriage outwardly.

35. In apparatus of the character described, in combination, a phonograph disk record compartment, accessible through one side, a slidable carriage frame therein adapted to seat a record, and to expose it at the said side, an arm substantially in the plane of said record having a part extending in front thereof, and means connecting said arm to said frame, to render said arm inobtrusive when said frame is slid outwardly.

36. In apparatus of the character described, in combination, a phonograph disk record compartment, a movable carriage frame therein, adapted to seat a record, an arm pivoted at a point fixed with respect to said compartment, and extending in the path of said record to prevent removal thereof, and means connecting said arm to said frame, to cause the former to move about its pivot to inobtrusive position when said frame is moved outwardly.

37. In a cabinet for phonograph disk records, in combination, a compartment, a slidable carriage frame therein, adapted to seat a record, an arm pivoted about an axis transverse of said compartment and extending in the path of said record to prevent removal thereof, and a second arm pivoted about the same axis and connected to the said first arm, and having a pin and slot connection with said frame.

38. In a cabinet for phonograph disk records, in combination, a plurality of compartments, a carriage frame in each compartment, adapted to seat a record, a bearing rod extending transversely of all said compartments, a bell crank lever in each said compartment, pivoted about said rod,

- each said lever comprising a locking arm for a record, and a shifting arm connected to the corresponding frame.
39. In a cabinet for phonograph disk records, in combination, a compartment, a slidable carriage frame therein, adapted to seat a record, a curved arm pivoted about an axis transverse of said compartment, to extend partially around the forward edge 10 of said record, and a second arm rigid with said first arm, and to one side of said record, said arm having a pin and slot connection with said frame near its free end.
40. In a cabinet for phonograph records, 15 in combination, a slidable carriage frame therein for seating a record, a stop locking bar pivoted to said frame, and weighted at its upper end to urge said end forwardly, but restrained against forward movement by 20 said record, whereby, upon removal of said record, a portion of said stop bar will prevent sliding said frame to home position, until a record is inserted therein to release said stop bar.
41. In a cabinet for phonograph records, 25 in combination, a slidable carriage frame therein for seating a record, means urging said frame outwardly, locking means opposing said urging means, and a stop locking bar urged to have a portion thereof interposed between said frame and the rear of said cabinet and restrained by said record, whereby, when said locking means is released said frame moves forwardly, and 30 when said record is removed, said frame cannot be replaced to home position until the record is reinserted.
42. In a cabinet for phonograph records, 35 in combination, a slidable carriage frame therein for supporting a record, a spring for urging said frame outwardly, locking means for opposing said spring, an arm for preventing removal of said record when said locking means is operative, and a stop locking bar pivoted to said frame, and urged to move its upper end forwardly, but restrained by said record.
43. In a cabinet for phonograph records, 40 in combination, a slidable carriage frame therein for supporting a record and a pivoted member connected to said frame and adapted to contact a part of said cabinet, for limiting the movement of said frame away from home position.
44. In a cabinet for phonograph records, 45 in combination, a slidable carriage frame therein for supporting a record, a pivoted member connected to said carriage, and adapted to contact a part of said cabinet, for limiting the movement of said carriage 50 away from home position, and means to prevent replacing said frame in said home position when empty.
45. In a cabinet for phonograph records, 55 in combination, a movable carriage frame therein for supporting a record, a locking arm pivoted to said frame for preventing removal of said record when said frame is in home position, and means urging said arm against the top of said cabinet, to limit the 60 displacement of said frame and to release said record.
46. In a cabinet for phonograph records, 65 in combination, a slidable carriage frame therein for supporting a record, a locking arm pivoted to said frame, for preventing removal of said record when said frame is in home position, means urging said arm against a part of said cabinet to limit the 70 displacement of said frame and to release said record, and means to prevent replacing said frame in said home position, until a record is reinserted therein.
47. In a cabinet for phonograph records, 75 in combination, a slidable carriage frame therein for supporting a record, a spring for urging said frame outwardly, locking means for opposing said spring, an arm for preventing removal of said record when said locking means is operative, a stop locking bar pivoted to said frame, and urged to move its upper end forwardly, but restrained by said record, said arm serving to limit the return slide of said frame.
48. In apparatus of the character described, 80 in combination, a compartment, a retaining member adapted to hold an article, means preventing removal of said article when said retaining member is in home position, a connection between said retaining member and said means for rendering the latter inoperative when the former is displaced, and a latch for maintaining said retaining member in home position.
49. In a phonograph record cabinet, in 85 combination, a compartment, a carriage frame therein, a locking arm for locking a record thereto, a latch for locking said frame to said cabinet, and a shifting arm connecting said locking arm to said frame, to release the former when said latch is 90 released, and said frame displaced.
50. A key for a phonograph record cabinet, comprising a handle, a shank, two bits at right angles to each other and at different parts of the length of said shank, and a transverse flange adjacent said handle, 95 said flange having a notch.
- Signed at New York city in the county of New York and State of New York this 120 31st day of May, A. D. 1919.
